UNITED STATES PATENT OFFICE

93,960

DESIGN FOR A MOTOR VEHICLE CAB

Frank G. Alborn and Viktor Schreckengost,
Cleveland, Ohio, assignors to The White Motor Company, Cleveland, Ohio, a corporation of Ohio

Application August 22, 1934, Serial No. 53,023

Term of patent 14 years

To all whom it may concern:

Be it known that we, FRANK G. ALBORN and VIKTOR SCHRECKENGOST, citizens of the United States, residing at Cleveland, in the county of Cuyahoga and State of Ohio, have invented a new, original, and ornamental Design for a Motor Vehicle Cab, of which the following is a specification, reference being had to the accompanying drawing, forming part thereof.

We claim:

The ornamental design for a motor vehicle cab, as shown.

FRANK G. ALBORN.
VIKTOR SCHRECKENGOST.
